RALPH C. SIMMONS, OF BEVERLY, MASSACHUSETTS, ASSIGNOR TO UNITED SHOE MACHINERY COMPANY, OF PATERSON, NEW JERSEY, A CORPORATION OF NEW JERSEY.

CUTTING-MACHINE.

1,129,131.

Specification of Letters Patent. Patented Feb. 23, 1915.

Application filed March 20, 1913. Serial No. 755,672.

To all whom it may concern:

Be it known that I, RALPH C. SIMMONS, a citizen of the United States, residing at Beverly, in the county of Essex and State of 5 Massachusetts, have invented certain Improvements in Cutting-Machines, of which the following description, in connection with the accompanying drawing, is a specification.

10 This invention relates to machines for cutting sheet material, and particularly to machines for cutting out blanks from such material by means of a die. In a common type of machine of this character the die is 15 subjected to pressure between members that have provision for relative movement so as to force all portions of the cutting edge of the die simultaneously through the stock.

An important object of the present invention is to effect an improvement in machines of this general type whereby less power will be required to operate the machine and the latter may be made lighter in construction without the danger of excessive strain upon 25 the mechanism.

With this end in view the invention contemplates the provision of a machine which will operate to force different portions of the cutting edge of the die successively into 30 or through the stock, thereby performing the cutting operation in a progressive manner.

It further contemplates, as one preferred embodiment of means for effecting the general object in view, an arrangement whereby 35 a die is placed with its cutting edge opposite and preferably in contact with material to be cut, and is then subjected to pressure upon its inactive face, first at or near one 40 side of the latter and then at points successively approaching the other side, whereby the cutting edge is forced progressively and evenly through the stock.

A more particular object of the invention 45 is to effect improvements in a type of machine used extensively at the present time especially for cutting out blanks from upper leather in the manufacture of boots and shoes, and known commercially as the 50 "clicking" machine.

In the operation of this machine, as usually constructed, the die is subjected to pres-

sure, in the nature of a quick blow, by the relative approach of coöperating presser members between which the die is placed. 55 My invention, in its illustrated preferred embodiment, provides for relative movement of such presser members in the path of their approaching movement, whereby different portions of their opposed faces successively reach their limit of approach and the die between such faces is thus subjected to pressure progressively along its cutting edge from one side to the other.

In the commercial type of clicking machine the presser member is secured at one end to a post that is mounted to reciprocate in vertical bearings at the rear of the bed, and projects freely over the bed, so as to contact with the die on the downward movement of the post. It is a natural incident to such a construction, and it has been found true in practice, that the presser member near its outer projecting end is less certain and positive in its action upon the die than 75 at portions that are nearer to the post. This is because of the manner in which the member is mounted and operated, whereby portions thereof farther from the post are subject in greater degree to that slight unavoidable upward swing of the member in its operation upon the die, which is incident to the wear of the post in its bearings, the inertia of the member on its sudden downward movement, and the tendency of the 85 frame of the machine, however strongly constructed, to spring somewhat under the action of the presser member on the die. The difficulty is increased when a large die is in use, since in such a case one portion of 90 the die may be located near the rear of the bed where the range of yielding movement of the presser member is small and another portion may be near the front of the bed where it is encountered by the outer free end 95 of the presser member at a point considerably farther from the post where the range of yielding movement is relatively large.

To avoid the difficulty it is customary to raise slightly the front edge of the cutting block and to vary as necessary the limit of relative approach of the presser member and bed. It has been found, however, that when proper adjustments have been made

for the use of a large die the machine will not operate in its most effective manner with a small die without further adjustment, and vice versa, and that the difficulty 5 is exaggerated where a cutting block formed of some hard and resistant material such as metal or a composition thereof is in use. With the object of avoiding these difficulties my invention embodies a construction 10 wherein the die is subjected at all portions of its cutting edge to sufficient positive pressure to assure a clean cut through the stock without unduly increasing the pressure or resistance where any portion of the cutting 15 edge encounters the hard material of the block. An important feature of such a construction consists of means whereby one of the co-operating presser members has provision for yielding movement in the path of 20 relative approach of said members against resistance suitably proportioned to effect a positive cut through the stock but to yield to the greater pressure of the die against the surface of the block. 25 In its preferred embodiment the invention contemplates further provision whereby the presser member, while yielding to a certain degree of pressure encountered at one portion of the die, will successively bring increased pressure to bear upon other portions of the die, thereby effecting the cutting 30 operation in the progressive manner previously referred to with a relatively small amount of power and without the danger of 35 excessive strain upon the machine under any working conditions.

Another object of the invention, in connection with the use of a projecting presser member mounted to swing yieldingly in the 40 path of its movement toward the bed, is to provide means to compensate suitably for the difference in effective action of the member at different distances from its pivotal point due to the differences in effective leverage. Such means comprises preferably 45 a toggle device combined with some resistance member such as a spring, so arranged that the toggle will approach its straight line position, or position of least resistance, 50 as the presser member contacts with the die at points successively nearer to the post, or in other words, as the effectiveness of the member, considered as a lever operating against the resistance of the spring, decreases. 55 This assures that all portions of the die shall be subjected to substantially the same pressure. Provision is also made for initiating positively the movement of the toggle at a predetermined point in the approach 60 of the presser member to the bed in case a die is not so located as to receive the contact of that portion of the member which is normally nearest to the plane of the bed. As a result of this the die will receive substantially 65 the same pressure wherever it may

be located upon the bed and whatever the size of the die may be. The features detailed combine to prevent that rapid wear of the cutting block and the consequent necessity of resurfacing often encountered in cutting machines, and also make it feasible, in view of the comparatively light and even pressure to which the die is subjected, to use a block formed of some composition of metal, which is less cumbersome than blocks made of wood or similar material and is not so easily scarred. 70

A further feature of the invention resides in the provision in a machine of the type referred to of means for adjusting the position of the cutting bed with reference to the presser member, and means conveniently located for indicating the proper position for the bed whatever may be the depth of the die in use. 80

A further object is to provide simple and effective means for actuating the mechanism that operates the presser member. 85

Other features and objects of the invention will appear from the following detailed description and will be pointed out in the claims. 95

The accompanying drawing is a view in side elevation and partly in vertical section of a machine embodying a preferred form of the invention. 95

Supported upon the front portion of the frame 2 of the machine is the table 4 which is formed with flanges 6 arranged to slide in vertical guideways 8 on the frame. Seated at one end upon a projection of the frame is the spindle 10 provided with a hand wheel 12 and having screw threaded engagement with the table at 14. The spindle thus provides a means of support and of vertical adjustment for the table. Resting upon the table is the cutting block or bed 16 which in this machine may be, and preferably is, formed of some composition of metal. A clamp 18 upon the table serves to hold the cutting block in place. The block or bed is intended to support, in the operation of the machine, a sheet of material 20, which may be a portion of upper leather from which blanks are to be cut for use in the manufacture of boots and shoes, and a die 22 which is to be placed in the desired position with its lower or cutting edge in contact with the stock and its upper or inactive face arranged in position to receive the contacting pressure or blow of an operating member to be described. 110

Mounted for turning and reciprocating movement in bearings 24 and 26 of the frame is a post 28 which is swiveled at its lower end upon a stud 30 and rests upon ball bearings 32 carried by the stud. The stud 30 has pivoted thereto an arm 34 which forms a strap encircling the eccentric 36 on the operating shaft 38. This shaft has 130

mounted loosely upon one end thereof an operating pulley 40, and a clutch is provided by which this pulley may be connected with the shaft at the will of the operator, so as to impart reciprocatory movement to the post 28. This clutch is preferably such as to impact at each actuation thereof a single reciprocation to the post 28, but its features are not shown in detail, since 5 this member, and likewise the brake device 42 which is arranged to stop the post automatically at the upward limit of its movement, may be the same as used in the commercial type of clicking machine and as 10 shown, for example, in United States Letters Patent 921,503 granted to Arthur Bates, May 11, 1909. A lever 44 has connections for tripping or actuating the clutch and is arranged to be operated by means which 15 will be subsequently described.

Mounted upon the post 28 so as to turn or reciprocate bodily therewith is the die operating arm or presser member 46. This member is pivoted to the post at 48 so that 20 it may have a swinging movement in the path of its movement toward or from the cutting bed. Encircling the post is a spring 50 which is mounted between the fixed collar 52 and the movable collar 54. Carried by 25 the post also is a toggle device which comprises a member 56 partly surrounding the post and pivoted thereto and forming one arm of the toggle, and links 58 pivoted to this arm at one end and at the other end pivoted 30 to the collar 54 and forming the other member of the toggle. Links 60 connect the toggle with the upper portion of the presser member. Although only one of the links 35 58 and 60 respectively is shown on the drawing, it will be understood that similar links 40 will preferably be arranged on the other side of the machine. It will be seen that with this construction, the presser member is supported yieldingly for swinging movement 45 about its pivot 48, and is arranged in a predetermined normal position with respect to the plane of the cutting bed. Preferably this member will be arranged as shown with 50 its lower or contacting surface somewhat inclined to the plane of the bed and with the forward portion of this surface nearer the bed than the rear portion. The normal incline of this member with respect to the bed will depend, it is clear, upon the position 55 of the collar 54 upon the post, and an adjusting screw 62 is provided for varying the position of this collar and consequently the normal predetermined inclination of the lower surface of the presser member with 60 respect to the bed. The presser member will be formed preferably with a contacting surface which is somewhat curved in the direction of the length of the member, as shown at 64.

65 It will be understood that the presser

member is intended to receive its swinging movement about the pivot 48 in opposition to the action of the spring and toggle through the resistance encountered by the contact of this member with the die on the 70 downward movement of the post. With the presser member inclined, as shown, its lower surface will contact first with that side of the die which is nearer the front end of the member, and will then, as the presser member 75 continues its downward movement and swings about its pivot, contact with the die at points successively approaching the rear. In this operation the presser member acts as a lever arm against the resistance of the 80 spring and toggle, and it will be apparent that the effective length of this arm is constantly decreasing as the member contacts successively with different portions of the die. At the same time, however, the toggle 85 is approaching its straightened position so that the normal decreasing effectiveness of the lever is substantially compensated for by the decreasing resistance of the toggle and spring. The purpose and effect of this arrangement is that the presser member shall 90 subject the die at all portions of its cutting edge to substantially uniform pressure against the stock and bed. It will be evident, however, that with the arrangement so 95 far described, if the die were placed upon the stock near the front of the cutting bed, the general average of pressure thereupon would be less than if it were placed near the rear of the bed, since the effective length of 100 the lever arm at the point of primary contact of the presser member with the die would be greater in the former instance. To obviate this difficulty, I have provided means for initiating the upward swinging 105 movement of the presser member at a predetermined point in the approach of this member to the bed. This means comprises an arm 66 projecting upwardly from the toggle member 56 and formed with an inclined cam portion 68 which is arranged to engage with an abutment, such as a roller 70 mounted in a forked projection 72 of a collar 74, on the downward movement of 110 the post. The collar 74 rests upon the upper portion of the frame and loosely encircles the post and is restrained from upward movement by means of a clamp 76. The arm 66 is arranged between the projections of the fork 72 so that on a swinging movement of the presser member and turning of 115 the post to one side or the other, the collar will be carried therewith and the roller will thus be presented for contact with the cam surface 68 in any lateral position of the 120 presser member with respect to the bed.

The cam member 68 is so arranged with reference to the abutment that if the die is located at the front of the bed, the presser member will contact with the die before the 125

cam comes in contact with the abutment, and the positive mechanism for operating the toggle will thus be ineffective. If the die is placed, however, somewhat toward the rear of the bed, the contacting face of the presser member because of its inclination will not meet the die so soon in the downward movement of the member, and in such case the cam 68 first encounters the roller 70 and the bending of the toggle and swinging movement of the presser member are initiated before the latter comes in contact with the die. The toggle will thus be somewhat straightened before the resistance of the die is encountered, and the resistance of the toggle and spring will be adjusted positively in proportion to the shorter effective leverage of the presser member by virtue of its contact with the die at a point somewhat nearer to the post. Through this means the presser member will subject the die to substantially the same average pressure wherever the die may be located upon the bed. This assures a clean cut through the stock and prevents that rapid wear of the cutting bed which is encountered where one portion of the die is subjected to a greater pressure than another portion. It also makes it feasible to employ a cutting bed formed of some composition of metal without destructive effect upon the cutting edge of the die. It should also be noted that the positive means provided for swinging the presser member would prevent the forward portion of this member from coming in contact with the bed in case the machine should be operated accidentally with no die in position, an action which otherwise might occur in view of the forward inclination of the presser member.

The starting device for actuating the clutch comprises a rod 78 connected at one end to the lever 44 previously referred to and at its other end to a lever arm 80 pivoted upon the frame of the machine and held by a spring 81 at the limit of its downward movement. Mounted upon the forward end of the presser member is a handle 82 by which this member is swung to different positions above the bed in the manner usual in this type of machine. For moving the lever 80 upward and thereby actuating the clutch, I have provided a novel arrangement which comprises a flexible cord 84 connected with the lever and having connection also with a pivoted portion 86 of the handle 82. This cord is guided by a pulley 88 mounted on a holder 90 which is swiveled in the upper end of the post 28 and is held in swiveled position by a screw 92, the reduced end of which engages in an annular groove in the depending stud 94 of the holder. This provides a simple and convenient arrangement by which the operator may first swing the presser member to operative position and then by a slight pressure or grip-

ping movement of his hand effect a pull upon the cord and thereby actuate the clutch. As the post descends, the pulley 88 is of course carried downward therewith and the cord is therefore loosened so that the parts of the tripping arrangement at the rear of the machine necessarily return to their starting position through the action of the spring 81 at the beginning of the downward movement of the presser member. The pulley 88 is provided with deep flanges so as to prevent the cord when loosened from becoming disengaged therefrom. Since the holder for the pulley is swiveled in the top of the post, the pulley may turn somewhat to one side or the other in proportion to the swinging movement of the presser member to one side or the other with respect to the bed.

In order to indicate the proper point for the adjustment of the table 4, especially where dies differing in height are in use, I have provided a gage which consists preferably of a bent rod 96 swiveled in a socket 98 in the frame and having an end portion 100 projecting in a plane which the upper face of the die should meet on the adjustment of the table and parallel to the plane of the bed. The gage thus indicates the proper position for the upper face of the die with reference to the limit of operative movement of the presser member toward the bed. The gage, when not in use, may be swung aside out of the range of operative movement of the presser member, or may be easily removed from the machine.

The principal features of operation of the machine have been pointed out in the preceding description. To recapitulate briefly, the operator, after adjusting the table to proper position to suit the depth of die in use, arranges upon the bed a sheet of material such as a piece of upper leather and places the die in a suitable position thereupon with its cutting edge in contact with the material. By means of the handle 82 he then swings the presser member to position over the die, and by a slight compression of his hand moves the portion 86 of the handle so as to pull upon the cord and actuate the clutch. By the clutch operated means the presser member is then moved quickly downward toward the bed, and if the die is arranged near the front of the bed the presser member contacts with the die before the cam 68 becomes effective to cause the arm 66 to swing and operate the toggle. The presser member contacts with the die first on that side which is nearer the forward end of said member and on its continued downward movement begins to swing upwardly about its pivot 48 against the resistance of the spring and toggle. This brings other portions of the curved surface 64 downward in contact with the die and thereby brings

pressure to bear upon the die at points successively nearer to the post. As a result of this operation, the die cuts the stock first at one side and then progressively toward the other side until the whole blank has been cut. At the same time that portion of the blade which first becomes effective is relieved of any excessive pressure which would tend to force the blade unduly into the surface of the bed. The arrangement of the spring and toggle device, as previously pointed out, assures that all portions of the die shall be subjected to substantially the same pressure. In case the die is placed somewhat toward the rear of the bed, the cam 68 and roller 70 become effective to begin the straightening of the toggle before the presser member contacts with the die. This assures, as previously explained, that the die shall be subjected to substantially the same pressure wherever it is placed upon the bed. After the cutting operation the presser member returns immediately and automatically to its starting position at the upward limit of its movement, and may then be swung aside to permit the die to be placed in some other position upon the stock, when the above described operations may be repeated.

Although I have described a machine in which a die is placed with its cutting edge resting upon a sheet of stock supported upon a stationary cutting bed and a presser member is moved into contact with the die, it should be understood that I contemplate simply relative movement of the presser member and bed, which constitute, in effect, co-operating presser members with respect to which the die and material to be cut may be arranged in various ways to effect the cutting operation. It should be understood also that the invention in many of its aspects is not limited to the other precise features and details of construction shown in the illustrated preferred embodiment thereof, but is susceptible of various other embodiments.

Having described my invention, what I claim as new and desire to secure by Letters Patent of the United States is:

1. A machine for cutting blanks from sheet material having, in combination, a die supporting bed, pressure applying means including an arm arranged to project over the die upon the bed, and means for operating said pressure applying means while the arm remains in the same plane perpendicular to the die to cause said means to co-operate successively with different portions of the die so as to cut the material progressively.

2. A machine for cutting blanks from sheet material having, in combination, a bed upon which may be located a free movable die with its cutting edge opposed to the ma-

terial, pressure applying means including an arm arranged to be swung about an axis at one side of the bed to a position over the die wherever the die may be located upon the bed, and means for operating said pressure applying means to cause said means to apply pressure successively to different portions of the die so as to cut the material in a progressive manner.

3. A machine of the class described having, in combination, a cutting bed for supporting a sheet of material and a die, and pressure applying means including an arm provided upon the side thereof opposed to the bed with means for engaging the die, and means for operating said pressure applying means to cause different portions of said engaging means to engage the die successively.

4. A machine for cutting blanks from sheet material having, in combination, a die supporting bed, pressure applying means including an arm movable about an axis located at one side of the bed to different positions above the bed, and means operative in any position of said pressure applying means to cause said pressure applying means to bring pressure to bear upon different portions of the die successively.

5. A machine of the class described having, in combination, co-operating presser members one of which is arranged to support material to be cut and to support also a cutting die, and means for moving one of said members toward the other, said members having provision also for relative movement angularly with respect to the direction of said first named movement to cause different portions of the die successively to cut the material.

6. A machine of the class described having, in combination, co-operating presser members arranged to receive therebetween a sheet of stock and a die, and means for imparting to said members relative bodily movement to bring them into pressure applying relation to the die, said members being relatively movable also during said pressure applying movement to bring pressure to bear successively upon different portions of the die, thereby effecting the cutting operation in a progressive manner.

7. A machine of the class described having, in combination, a bed for supporting a sheet of stock and a die, and a presser member movable bodily downward toward the bed and into pressure applying relation to the die, said member being movable also during said pressure applying movement to cause it to press successively upon different portions of the die, thereby effecting the cutting operation in a progressive manner.

8. A machine of the class described having, in combination, a die-supporting bed, and a presser member movable bodily to-

ward the bed in a direction substantially perpendicular thereto and constructed and arranged to engage the die primarily at one side of the latter, said member being mounted also for angular movement with respect to its direction of movement toward the bed, whereby continued bodily movement of the presser member toward the bed serves to effect a relative movement of said member in the path of said first named movement and engagement thereof successively with other portions of the die.

9. A machine of the class described having, in combination, a bed, a presser member movable bodily toward the bed, and operating means for the presser member, said member being so connected with its operating means as to swing in the path of its movement toward the bed during the pressing 15 operation.

10. A machine of the class described, having, in combination, a die-supporting bed, and a presser member movable bodily toward the bed, said member being mounted 25 for swinging movement in the path of its movement toward the bed and having a curved contacting face to coöperate with the die.

11. A machine of the class described having, in combination, a die-supporting bed, and a presser member movable bodily toward the bed and into engagement with the die, said member being mounted for swinging movement in the path of its movement 35 toward the bed and having its contacting face normally inclined to the plane of the bed.

12. A machine of the class described having, in combination, a die-supporting bed, 40 a presser member movable bodily toward the bed and into engagement with the die, said member being mounted for swinging movement in the path of its movement toward the bed and having its contacting face normally inclined to the plane of the bed, and means for varying the degree of such normal inclination.

13. A machine of the class described having, in combination, a bed, a presser member 45 mounted for bodily movement in a direction normal to the plane of the bed and arranged to engage a die upon the bed, said presser member having its engaging face curved in the plane of said bodily movement and being mounted also for angular movement with respect to the direction of said bodily movement to cause different parts of the die to be 55 acted upon successively by said curved face.

14. A machine of the class described having, in combination, a bed, a presser member 60 movable bodily toward the bed, said member being mounted for swinging movement in the path of its movement toward the bed, and means for opposing yielding resistance

to said swinging movement of the presser member in a direction away from the bed.

15. A machine of the class described having, in combination, a bed, means movable toward the bed for applying pressure to a die upon said bed, said means including a member pivotally mounted for yielding movement in the path of said first named movement, and a spring for opposing resistance to the yielding movement of said member.

75
16. A machine of the class described having, in combination, a bed, a post mounted to reciprocate at one side of the bed, a presser member pivotally connected at one point with the post and movable bodily toward and from the bed on reciprocation of the post, and means connecting the presser member at another point to the post including a spring for opposing yielding resistance to the pivotal movement of said member.

80
17. A machine of the class described having, in combination, a bed, a presser member movable bodily toward the bed, said member having provision for relative movement in the path of its movement toward the bed, and means for opposing a yielding and progressively decreasing resistance to said relative movement of the member.

85
90
18. A machine of the class described having, in combination, a bed, a presser member movable bodily toward the bed, said member being mounted for swinging movement in the path of its movement toward the bed, a spring for resisting said swinging movement of the presser member in a direction away from the bed, and a toggle device forming a connection between said member and spring.

95
100
105
110
115
120
125
19. A machine of the class described having, in combination, a frame, a post mounted to reciprocate in the frame, a bed, a presser member carried by the post and extending over the bed, said member being movable bodily toward and from the bed on reciprocation of the post and being pivotally mounted on the post so as to swing in the path of said movement, and means for opposing yielding resistance to the swinging movement of the presser member in a direction away from the bed, said means comprising a spring carried by the post, a toggle device also carried by the post and arranged to be operated against the resistance of the spring, and means connecting the presser member with said toggle device.

20. In a machine of the class described, the combination with a die-supporting bed, of a presser member movable bodily toward the bed and pivoted also to swing simultaneously in the path of said bodily movement, said member being arranged to engage the die primarily at the side thereof

- remote from the pivotal axis of said member and in swinging about said axis to engage the die at points successively nearer to said axis, and means for opposing a yielding and progressively decreasing resistance to such swinging movement of the presser member.
21. A machine of the class described having, in combination, a die-supporting bed, 10 a presser member movable bodily toward the bed and pivoted to swing relatively in the path of said bodily movement on engagement with the die, and means for opposing a yielding and progressively decreasing resistance to such swinging movement of the presser member comprising a spring, and connections between the spring and the presser member including a pair of toggle links arranged to approach a straight 15 line position on the swinging movement of said member.
22. A machine of the class described having, in combination, a bed, a presser member movable bodily toward the bed, said member being mounted for swinging movement in the path of its movement toward the bed, and means for initiating the swinging movement of said member in a direction away from the bed at a predetermined point in the approach of said member to the bed.
23. A machine of the class described having, in combination, a frame, a post mounted to reciprocate in the frame, a bed, a presser member carried by the post and 35 extending over the bed, said member being movable bodily toward and from the bed on reciprocation of the post and being pivotally mounted on the post so as to swing in the path of said bodily movement, means for opposing yielding resistance to the swinging movement of the presser member in a direction away from the bed comprising a spring and a toggle device, and means for initiating the swinging movement of said member in a direction away from the bed at a predetermined point in the approach of 40 said member to the bed, said means comprising an arm connected with one of the members of said toggle device and having a cam portion arranged to engage a relatively fixed abutment and thereby act to operate the toggle at a predetermined point in the movement of said post in one direction.
24. In a machine of the class described, 55 the combination with a presser member having a predetermined range of operative movement, of an adjustable cutting bed, and a gage removably mounted in the frame of the machine and having a portion projecting in position to indicate the proper plane for that face of the die which is engaged by the presser member.
25. In a machine of the class described, 60 the combination with a presser member hav-
- ing a predetermined range of operative movement, of an adjustable die-supporting bed, and a gage having a portion projecting in a plane parallel to the plane of the bed and arranged to indicate the proper position for the upper face of the die with reference to the limit of operative movement of the presser member toward the bed.
26. In a machine of the class described, 65 an adjustable cutting bed, and a gage for indicating the proper position of adjustment of the bed, said gage comprising a bent rod loosely swiveled in a socket in the frame of the machine and readily removable therefrom.
27. A machine of the class described having, in combination, a bed, a presser member movable initially to different positions with respect to the bed, a handle whereby such movement may be effected, automatic mechanism for imparting to said presser member operative movement with respect to the bed, and means for rendering said mechanism operative comprising a device arranged to act through a gripping movement of the operator's hand upon said handle.
28. A machine of the class described having, in combination, a bed, a presser member movable initially to different positions with respect to the bed, a handle whereby such movement may be effected, said handle having a portion thereof movable with respect to the main portion, automatic mechanism for imparting to the presser member operative movement with respect to the bed, and means for rendering said mechanism operative comprising a flexible cord connected to the movable portion of said handle and having also operative connections for actuating said mechanism.
29. A machine of the class described having, in combination, a bed, a presser member arranged for operative movement with respect to the bed, mechanism for imparting such movement to the presser member, and means for rendering said mechanism operative comprising a handle movably mounted on the presser member and a flexible cord connected with said handle and having also operative connections for actuating said mechanism.
30. A machine of the class described having, in combination, a frame, a bed supported thereon, a post supported for rotation and vertical reciprocation in said frame, a presser member mounted on the post so 100 as to swing therewith to different operative positions above the bed, means by which said presser member is moved to different operative positions comprising a handle mounted on said member, said handle having a portion thereof movable with respect to the main portion mechanism for reciprocating vertically said post and presser

member, and actuating connections for rendering said mechanism operative comprising a flexible cord connected with the movable portion of said handle, and a pulley 5 swiveled upon the top of the post by which said cord is guided.

In testimony whereof I have signed my

name to this specification in the presence of two subscribing witnesses.

RALPH C. SIMMONS.

It is hereby certified that in Letters Patent No. 1,129,131, granted February 23, 1915, upon the application of Ralph C. Simmons, of Beverly, Massachusetts, for an improvement in "Cutting-Machines," an error appears in the printed specification requiring correction as follows: Page 3, line 7, for the word "impact" read *impart*; and that the said Letters Patent should be read with this correction therein that the same may conform to the record of the case in the Patent Office.

Signed and sealed this 28th day of September, A. D., 1915.

[SEAL.]

J. T. NEWTON,

Acting Commissioner of Patents.
